S. P. HULL

RAILWAY SIGNAL

Filed Feb. 9, 1923

INVENTOR.

BY

ATTORNEY.

UNITED STATES PATENT OFFICE.

SAMUEL P. HULL, OF NEW YORK, N. Y.

RAILWAY SIGNAL.

Application filed February 9, 1923. Serial No. 618,157.

To all whom it may concern:

Be it known that I, SAMUEL P. HULL, a citizen of the United States, and resident of New York, in the county of New York and 5 State of New York, have invented certain new and useful Improvements in Railway Signals, of which the following is a specification.

This invention relates to railway signals 10 and includes certain novel features in construction and arrangement of parts whereby the indications of the signal are changed by moving a colored screen between a source of light and a lens. The lens is adjustable 15 with relation to its support in two planes at right angles to each other. The signal has a vertical support pivotally secured to a base so that it may swing through an arc to direct the indication from the signal. 20 This signal is particularly adapted for use on curves and grades and is illustrated in connection with a track switch, giving a plurality of indications of the position of 25 the switch points. The objects of the invention are more particularly described in the following specification and shown in the accompanying drawings, in which, Fig. 1, is an elevation of the signal complete, Fig. 2, is an elevation at right angles to Fig. 1, Fig. 3 is a plan view of the target used in 30 Figs. 1 and 2. Fig. 4 is an alternative construction to Fig. 3, showing the use of a semaphore. Fig. 5, is a sectional elevation of the interior of the signal lamp, Fig. 6 is 35 a plan view of Fig. 5. Fig. 6^a is another sectional view. Fig. 7 is a detail showing the construction of the lamp support and Figs. 8 and 9, show the application of the signal on a railway track.

40 The usual practice at hand-operated railway switches is to provide a switch stand which is spiked to the ends of long ties and has suitable connections for operating the switch rails by a hand lever. This stand 45 has a vertical shaft which is rotated through 90 degrees when the switch rails change position. On this shaft a target is provided having blades of different colors at right angles to each other and the shaft ends in a squared taper. A lamp having lenses 50 180 degrees apart is supported at the end of this shaft by a squared socket fitting over the taper.

In the present invention a signal is provided to indicate the position of the switch rails quite independently of the mechanism which operates the switch. This signal is supported on a stand or base of concrete at the side of the track and is operated mechanically by connection to the point of the 60 switch rail.

The light signal or lamp in the present invention is rigidly secured to its support and cannot be placed to give a wrong indication as might occur with a lamp placed on a square socket. The lamp being rigid, its focal plane can be adjusted in a particular direction and maintained in this direction with the result that the indication is increased in range and made more effective. 65 For the purpose of adjusting the focal plane, the position of the lenses are adjustable with relation to the lamp itself and the support of the lamp is adapted to be tilted from the vertical to correspond with conditions on 70 grades.

In the drawings, 11 represents a concrete foundation supporting the signal mast 12 to which the light signal or lamp 13 is rigidly secured. This mast also supports the target 80 having blades 14 and 15, Fig. 3 at right angles to each other for daylight indication and more particularly described hereafter.

The foundation 11 is provided with the usual foundation bolts 22 engaging the base plate as shown in Figs. 1 and 2. This base plate it will be noted has a sloping ridge developed to a point 23 under the centre, Fig. 2, so that the plate may turn about this point by adjusting the nuts on the foundation bolts 22 on either side. This will displace the plate 21 from the horizontal and correspondingly tilt the mast 12 supported by this plate. It will be noted that the mast is tiltable in the plane of the lenses 41 and 42 and the indication therefrom is directed accordingly.

A bracket 24 is clamped to the base of the mast and supports the operating crank 25 to which the operating rod 26 connects. 100 This bracket is usually designed so that the crank may be applied to either side of the mast. The up and down rod 27 connects to the crank and operates the revolving target and changes the light indication. 105 The target is secured to a sleeve 32 resting

on a collar 31 clamped to the mast 12. A rod 29, pivotally secured to a blade of the target at 30, connects with an arm 28 moving integral with crank 25 and so adjusted that a full stroke of the crank will move the target through 90 degrees, thus changing the indication. While the rotating target signal just described is commonly used on switches for daylight indications, 10 a semaphore type of indication can readily be substituted for the target as indicated in Fig. 4. In this case the semaphore 34 is pivoted at 35 to the mast 12 and by the connection 36 to the up and down rod 27 the semaphore is turned on its pivot to give the desired indication.

The lamp consists of a housing 13 secured by the socket 33 to the mast 12. This housing is provided with lenses 41 and 42 placed 20 opposite as shown. The lens ring is secured to a plate 42^a which is clamped by screws 43 in the slotted opening shown to plate 44. This plate, in turn, is clamped by screws 45 in a slotted opening to the housing 13. 25 From this construction, it will be noted that the position of the lens may be adjusted vertically and horizontally with relation to the casing 13. Each lens is adjustable independently of the other.

30 The source of light, as illustrated in Fig. 5, is an electric bulb 51, supported by a lamp bracket 52 in the vertical axis of the lamp housing and in line with the lenses. Interposed between the 35 source of light and the lenses is the colored shade 53—54 which is secured to the up and down rod 27 and is raised and lowered as this rod is operated by the switch rails. The top part of this shade is colored red and the 40 lower part is colored green, yellow or otherwise as desired. When the shade is lowered the red section 53 aligns with the lenses giving a red light indication; when the shade is raised, the section 54 aligns with the lenses giving a green light or other indication as arranged. It will be noted that the indication from both lenses is changed simultaneously. The red shade is preferably placed at the top so that should a disconnection of the up and down rod occur, 45 the signal will, by gravity, show danger. The colored shade as shown in the drawings is cylindrical but it is apparent this shade may be made in curved sections and perform the functions required by the invention.

As shown in Fig. 6 the cylindrical shade may be cut away to make space for the lamp bracket 52. This bracket is secured 60 to the housing 13 as shown in Fig. 7 in which 71 shows an oil fount or lamp base which must be adjustable vertically and horizontally to bring the light into the focus of the lenses. The bracket 52 has 65 a vertical end secured to the housing by the

screws 72 placed in the same vertical plane. This end is spaced from the housing by the screws 73 on the same horizontal plane. The bracket will pivot horizontally on the screws 72 and vertically on the screws 73. It is 70 apparent that these screws may be adjusted to tilt the end of the lamp bracket with a micrometer adjustment.

When the source of light is an oil lamp, the construction shown in Fig. 6^a may be 75 used. The lamp is placed in the housing as shown with a hood 57 to project beyond the edge of the housing. A ventilating cone 58 and a hood 59 is provided on top. From the hood 57 depends the frame 56 which supports the oil lamp. This part is removed as a whole for cleaning and trimming. With this type of signal having stationary lenses when the lamp is removed and placed on the track it cannot give a 80 color signal.

One application of this invention is shown in Fig. 8 where 61 is the stock rail and 62 is the switch rail. The signal makes direct mechanical connection to the point of the switch rail through rod 63, crank 64 and operating rod 26, the operating rod 26, however, may be connected directly to the switch rail or to the switch operating mechanism. 90

The application of this signal on a curve is illustrated in Fig. 9 in which 66 is the signal and 65 is the track. The lens of the signal pointing to the left is adjusted to throw a beam of light parallel to the track as indicated by *a* and the lens pointing to the right may be adjusted to throw a beam of light in the line *b*. The cylindrical shade permits these adjustments without affecting the indication. This shade may be constructed from glass, mica or other transparent material. The plates 42^a and 44 may be spherically formed so that in adjusting the lenses they will not be moved out of the focus of the light. 100

When applied on a grade it is apparent that the mast may be tilted so that the lenses are inclined to the horizontal corresponding to the grade. This makes the indication equally effective in both directions. 110

This signal has been shown and described in its application to indicate the position of track switches, but the principles herein disclosed may be used in the general application of light signals. 120

Having thus described my invention, I claim:

1. In a railway signal lamp, the combination of a lamp housing, a lens, a source of light and a cylindrical colored shade, said lens adjustable about the axis of said cylinder, said shade interposed between said light and said lens and means for imparting a vertical motion to said shade. 125

2. In a railway signal, the combination 130

of a lamp housing, a lens, a source of light and a cylindrical colored shade in two horizontal sections, said shade interposed between said light and said lens, the upper 5 section of said shade being colored red and means for imparting a vertical motion to said shade.

3. In a railway signal, the combination of a lamp housing, a lens, a source of light and 10 a cylindrical colored shade, said shade interposed between said light and said lens, said lens adjustable about the axis of said cylinder, said shade having sections of different colors and means for imparting a 15 vertical motion to said shade.

4. In a railway signal lamp, the combination of a lamp housing, a pair of lenses, a source of light and a colored shade, said lenses angularly adjustable about said light

as a centre, said shade interposed between 20 said light and said lenses and means for imparting a vertical motion to said shade.

5. In a railway signal lamp, in combination, a lamp housing, a lens adjustably secured to 25 said housing, a source of light and a movable colored member moving in the plane of said lens for changing the indication from said signal.

6. In a railway signal lamp, in combination, a lamp housing, a plurality of lenses 30 adjustably secured to said housing, a source of light and a colored member interposed between said light and said lenses.

Signed at New York, in the county of New York and State of New York, this fifth 35 day of February, A. D. 1923.

SAMUEL P. HULL.
